UNITED STATES PATENT OFFICE.

CHARLES B. COVENTRY, OF CHICAGO, ILLINOIS.

LOCOMOTIVE-BOILER.

SPECIFICATION forming part of Letters Patent No. 290,542, dated December 18, 1883.

Application filed November 7, 1883. (No model.)

To all whom it may concern:

Be it known that I, CHARLES B. COVENTRY, a resident of Chicago, Cook county, Illinois, have invented certain new and useful Improvements in Locomotive-Boilers, of which the following is a specification.

My invention is intended to be an improvement on the locomotive-boiler described and claimed in Letters Patent of the United States 10 to myself, dated October 30, 1883, and No. 287,505; and it has for its object the facilitating and increasing the draft in, particularly, return-flue locomotive-boilers.

Figure 1 is a vertical longitudinal section of 15 the fire and smoke boxes. Fig. 2 is a section of one of the water-legs, showing the corrugated inner wall and the steam-pipe. Fig. 3 is a perspective view of the fire-box end of the boiler, with a portion of the shell broken 20 away.

In the drawings, A represents the boiler or shell; B, the furnace or fire-chamber; C, the heating-flues; D, the return or superheating flues; E, a smoke-chamber located above the 25 crown-sheet, and into which the superheating-flues open; and F, a pipe leading from the upper or superheating portion of the boiler to the furnace or fire-chamber.

In constructing boilers with return or superheating flues, in which the heated products of combustion are required to twice traverse the length of the boiler, it has been found difficult to produce or secure a sufficient amount of draft to insure its practical and successful 30 operation. Various devices have been employed in boilers to produce this result, the most common of which has been to employ a jet of steam in the smoke-stack which would operate as a suction. In my improvement I 35 employ this draft or jet of steam in the fire-chamber so that it will operate as a force, either in conjunction with a jet in the smoke-stack or without, as may be deemed most desirable. I prefer, however, to emit a sufficient 40 quantity of steam under pressure into the fire-chamber to produce sufficient draft without the employment of a suction-jet.

In building a locomotive-boiler with my 45 improvements I take the boiler particularly shown and described in the patent to myself above referred to, and introduce the end of a

pipe into the upper or superheating portion of the boiler, which may be opened or closed by any ordinary cock or valve, and then lead the pipe down through the crown-sheet into 55 the furnace or fire-chamber. I then carry it back and forth across the top of the fire-chamber a number of times, and then bring it down the sides of the fire-chamber to within a few inches of the body of coal or burning-fuel, where I have it traverse the sides of the furnace one or more times, as may be desired. The end of the pipe in the fire-chamber is closed, and the lower length or lengths of the pipe is provided with fine perforations, to permit 60 the escape of the steam into the furnace. I prefer that at least one layer or length of the pipe should be arranged on each side of the furnace, so that the perforations would face each other.

The operation is as follows: When the fire has been built in the furnace and steam produced and raised to a sufficiently high temperature to be superheated in the upper portion of the boiler, the valve or stop-cock in the 75 upper end of the pipe F is opened by any convenient means, when the superheated steam, being already under a high pressure, will immediately rush in and down the pipe. When it reaches the coils or convolutions of the pipe 80 on the top and along the sides of the furnace, which are heated to a high degree by the fire, the steam will become still further expanded; and under the increased pressure thus produced will enter the furnace with great force 85 and velocity, and, mingling with the products of combustion, these jets or currents of superheated steam will rush through the flues and produce all the draft required to cause the heated products of combustion to twice traverse 90 a boiler even of the longest construction.

To prevent the pipe F from being melted by the great heat of the furnace, the roof and sides of the furnace may be corrugated or indented, so as to have channels or depressions in which 95 the coils or convolutions of the pipe may rest, so that the walls of the furnace will be comparatively smooth and but a small portion of the pipe exposed to the action of heat.

As before said, my improvement particularly relates to locomotive-boilers like the one described in my patent above, in which re-

turn superheating-flues are employed, and in which the difficulty of securing sufficient draft is greater than in boilers of the ordinary construction; but it is obvious that the principle 5 of my invention is equally applicable to locomotive-boilers with but one set of flues as ordinarily constructed. It is also apparent that mechanical changes may be made in the size, form, and location of the conveyer-pipe by 10 which the steam is furnished to the fire-chamber. I do not, therefore, wish to limit myself narrowly to these details of construction.

What I claim, and desire to secure by Letters Patent, is—

15 1. A locomotive-boiler provided with heating-flues, return superheating-flues, smoke-

chamber into which the superheating-flues open, and pipe leading from the superheating portion of the boiler into the furnace or firebox, to convey superheated steam into the same, 20 whereby the draft is facilitated and increased, substantially as described.

2. A locomotive-boiler in which the walls of the furnace are corrugated or provided with depressions, in combination with a pipe leading from the steam-space, and lying in such corrugations or depressions, substantially as described, and for the purpose set forth.

CHARLES B. COVENTRY.
